WASTEBASKET

John W. Fuller, 80 Skyline Drive, Morristown, N.J.
Filed Mar. 13, 1963, Ser. No. 264,820

1 Claim. (Cl. 220—4)

The invention relates generally to wastebaskets, and specifically to a wastebasket which may be quickly and easily assembled from its component parts.

It is an object of the invention to provide a wastebasket which may be easily assembled from its components, and may be prior to assembling it packaged, stored, sold and shipped in a relatively small, compact, flat package.

Another object of the invention is to provide a wastebasket which may be quickly and easily assembled by the ultimate purchaser without tools.

Yet another object of the invention is to provide an inexpensive, esthetically pleasing, durable wastebasket.

These objects and advantages may be attained by the article shown, by way of illustration of the invention, in the drawings in which

FIGURE 1 is a front elevational view of the assemblage with one retainer removed;

FIGURE 2 is a rear elevational view of a side panel;

FIGURE 3 is a front elevational view of a retainer;

FIGURE 4 is a rear elevational view of the retainer;

FIGURE 5 is a top plan view of the retainer;

FIGURE 6 is a bottom view of the retainer;

FIGURE 7 is a top plan view of the bottom;

FIGURE 8 is a partial cross-sectional view of the back corner of the assemblage taken on the line 8—8 in FIGURE 1, looking the direction of the arrows.

The design of the wastebasket is dictated in part by the desire to meet the demand of the mass-market for a product which is priced within the reach of the multitude. To reach this type of consumer, the price is low, the article is designed to be easily assembled by the ultimate purchaser, and thus may be shipped, stored, and sold in a small flat package. To merchandise an assembled basket would make the product much more expensive to assemble it, to store it, to package it for shipment, delivery or sale. The present device has five principal parts; there are four accessory parts, that enable the components to be assembled with speed and ease after delivery to the ultimate purchaser.

Referring now to the drawings in detail, the wastebasket is preferably rectangular with four side-panels 11 although it may be formed with a greater or lesser number of side panels. Each panel may be generally rectangular, or may be tapered with side edges 12 tapering toward the bottom 13. The side or vertical edges 12 of the side panels 11 are provided with enlargements 14 along the vertical edge 12 on one side, and opposing cooperative sockets 15, 15, etc. along the vertical edge 12 on the other side of the side panel 11.

Parallel to the vertical edges 12 of the side panels 11, and on the outer face thereof, and spaced a brief distance inwardly therefrom, vertical channels 16 are formed. The top of each channel is provided with a widened channel area 17, for ease in starting the insertion of retainers, as will be later set forth. Each panel 11 has on its inner face, near the bottom, a latitudinal rib 18 that defines

2

a seat for a bottom. Above the rib 18 are a plurality of enlargements 19, formed on the inner face of the side panel 11, and so spaced above the rib 18 as to act as tainers or detents to secure the bottom in seated engagement on the rib 18.

The side panels 11 are secured together in edge-to-edge relationship with the enlargements 14 inserted in the sockets 15 by the side panels being clinched together by retainers 20. These retainers 20 are relatively thin, longitudinally resilient but latitudinally relatively rigid metal strips having sides 21 relatively rigidly disposed at an angle (approximately 90°) to each other, and having flange edges 22 relatively rigidly disposed to the sides 21, 21 at an angle of approximately 90°; the edges 22 are adapted to enter the channels 16 at the wide area 17, and the sides 21 lie against the adjacent front face portions of the panels 11. At the top of each retainer 20, there are bent over portions defining pairs of detents 23. These bent over portions are triangular, and limit the insertion of the retainers 20 in channels 16. The retainers are sufficiently long so as to engage the entire length of the channels 16 with detents 23 engaged with the edge of the panel adjacent to the end of the channels 16.

The side panels 11 are preferably made of plastic sheet and may be clear, simulated tortoise shell, or any other chosen color, with a design, such as a simulated cut-glass applied thereto. A rectangular bottom panel 24 made of the same material, is also provided. It is dimensioned as to fit between the side panels 11 and to be seated on the rib 18, held down by the enlargements 19. The parts are rigidly and durably assembled, but may be disassembled by prying the retainers 20 out of the channels.

The foregoing description is merely intended to illustrate an embodiment of the invention. The component parts have been shown and described. They each have substitutes which may perform a substantially similar function; such substitutes may be known as prior substitutes for the said components and may have actually been known or invented before the present invention; these substitutes are contemplated as being within the scope of the appended claims, although they are not specifically catalogued herein.

What is claimed:

A wastebasket comprising

- (a) generally rectangular side-panels having mitred vertical edges,
- (b) opposing cooperative enlargements and sockets on the opposite vertical edges of the side panels, the enlargements extending generally parallel to the outer edges of the panel bearing its cooperative socket, the enlargements and sockets positioned to maintain the top and bottom edges of the panels in vertical registration and the vertical edges abutting panels in horizontal registration when the said cooperative enlargements and sockets are tightly engaged to each other;
- (c) generally vertical channels on the outer-faces of side-panels in parallelism and adjacent to the vertical edges,
- (d) retainers having sides relatively rigidly disposed at generally right angles to each other, and flange edges on the edge of each side relatively, rigidly, inwardly disposed at generally right angles to the side on which

is formed, the said flanges being slidably engaged with pairs of channels whereby the side panels are secured together in edge-to-edge relation with the enlargements and sockets engaged with each other,
) detents at the top of each retainer to limit the 5
) slidable engagement of the end of the retainers to the
 end of the channels by engagement of the detent
 with the edge of the panel adjacent to the channel,
) a widened channel area at the top of each channel,
) a longitudinal rib on the inner faces of each side- 10
 panel adjacent to the bottom thereof;
) an enlargement on the inner faces of each side-
 panel above the rib,
) a bottom-panel dimensioned to seat within the side- 15
 panels with its edges between the ribs and the en-
 largements on the inner face of the side panels.
